ATTORNEYS,

UNITED STATES PATENT OFFICE.

NOAH HARRIS, OF INDIANAPOLIS, INDIANA.

HEEL PLATE.

1,426,186.

Specification of Letters Patent. Patented Aug. 15, 1922.

Application filed January 13, 1922. Serial No. 529,020.

To all whom it may concern:

Be it known that I, NOAH HARRIS, a citizen of the United States, residing at Indianapolis, in the county of Marion and State 5 of Indiana, have invented new and useful Improvements in Heel Plates, of which the following is a specification.

My present invention pertains to wear plates for the heels of boots and shoes and 10 more particularly to the heels that are formed of rubber or other resilient material, and it contemplates the provision of a plate that is stamped from a single piece of suitable material and one that may be readily 15 applied to the outer surface of a heel and as easily and quickly removed.

The invention further contemplates the provision of a wear plate for heels that will in no way decrease the resiliency of the heel 20 and at the same time will materially prolong the life of the heel and add to its finished appearance.

The invention in all of its details will be 25 fully understood from the following description and claims when the same are read in connection with the drawings accompanying and forming part of this specification, in which—

Figure 1 is a top plan view of my novel 30 wear plate and showing the same as it appears when stamped from the sheet steel or other material.

Figure 2 is a perspective view of the plate 35 and showing the lugs as bent to their proper position ready to apply to a heel.

Figure 3 is a transverse section of a heel and showing my novel plate applied thereto.

Figure 4 is an inverted plan view of my 40 novel plate applied to a heel.

Similar numerals of reference designate 45 corresponding parts in all the views of the drawings.

My novel plate comprises the body portion 1 that may be of the shape and size 50 shown or any other suitable size and shape as may suggest itself and on one side thereof I provide the lug 2 having the longitudinal slot 3 and on the opposite side of the body portion 1 I form an integral lug 4 that 55 is provided at its extreme end with the point 5 and the said lug 4 like the lug 2 is further provided with the longitudinal slot 6.

The wear plate is stamped from sheet steel 60 or other suitable material and when produced comprises the said lugs 2 and 4 as well 65 as the slots 3 and 6 and point 5. The lug 3

is then bent at right angles to the plate body portion 1 and the lug 4 is bent at an angle of approximately 45 degrees with respect to the body portion 1 all as clearly appears in 60 Figure 2.

My novel wear plate is secured to a heel 9 of rubber or other suitable material by simply making an incision in the heel with a large awl and driving the point 5 of lug 4 65 into the incision from the outer wear surface of the heel and this driving of the point 5 will cause it to assume the position shown in Figure 3. A barbed nail is then driven through the material of the heel from the 70 wear surface side until it enters the longitudinal slot 6 of the lug 4 and it will be particularly noted that the said barbed nail 8 is driven so that it rests at the extreme upper end of the slot 6. This provision is 75 made in order that the resiliency of the heel remain intact and pressure exerted on the wear body portion 1 will force the lug upwardly and downwardly with respect to the nail 8.

The chief function of the nail 8 by touching upper end of slot 4 is to prevent backward movement of plate 1 and hence loosening of nail 7 is prevented.

When the securing of the lug 4 has been 80 accomplished it is then simply necessary to drive barbed nail 7 into the extreme upper end of the slot 3 of the lug 2 and from this it will be seen that pressure on the plate body portion 1 will permit the lug 2 to ride 85 upwardly on the barbed nail 7 and downwardly to its normal position when the pressure 1 has been temporarily relieved.

I have shown the wear plate as applied and having the lugs 2 bearing on the rear 90 peripheral edge of the heel but in the future practice of the invention it is to be distinctly understood that the plate may be applied at any suitable point on the peripheral edge of the heel.

It will be manifest from the foregoing that notwithstanding its simplicity and inexpensive construction the plate will materially prolong the life of the heel and may be as readily applied to a resilient heel and 105 when applied to this type of heel does not defeat the purposes for which said heels are intended.

Having described my invention what I 110 claim and desire to secure by Letters-Patent is:—

In a wear plate for rubber heels, compris-

ing a body portion of oval shape, lugs formed integral on the periphery of the body portion; one of the lugs extending at right angles to the body portion and adapted to bear against the back of the heels and the other of the lugs extending at an approximate angle of forty-five degrees with respect to the body portion and having a pointed end whereby the last named lug may be forced into the heel, each of the lugs having elongated slots therein to receive

fastening means whereby pressure exerted on the plate will cause the fastening means to move in the slots.

In testimony whereof I have hereunto set my hand in presence of two subscribing witnesses.

NOAH HARRIS.
